UNITED STATES PATENT OFFICE

CHRISTIAN VON HOFE, OF VIENNA, AUSTRIA, ASSIGNOR TO C. P. GOERZ OPTISCHE AN-
STALT AKTIENGESELLSCHAFT, AKCIOVA SPOLECNOST K. P. GOERZ OPTICKY USTAV,
OF BRATISLAVA, CZECHOSLOVAKIA, A CZECHOSLOVAK COMPANY

SOUND-DIRECTION-DETERMINING APPARATUS

Application filed April 18, 1928, Serial No. 271,006, and in Germany May 7, 1927.

In sound direction determining apparatus for finding invisible aircrafts and which, according to the prior Patent No. 1,649,538, consists of bodies of revolution confocally connected with each other and serving as sound receiving and leading reflectors, the axes of revolution of which usually intersect each other at an angle of 90°, the natural vibrations of the ellipsoidal sound leading reflectors are sometimes perceptible as a serious disturbance and before all, if the natural tone of the sound leading reflector, produced by all possible air vibrations occurring comes near the pitch of the tone of the aircraft.

These disturbances may be prevented according to the invention by providing the sound leading reflectors with one or more longitudinal slots preferably in that plane which takes the least part in the reflection of the sound, that is to say the meridian plane perpendicular to the acoustic axis of the preceding reflector which slots may be covered with some soft material such as leather, rubber balloon fabric and the like cemented thereover, for preventing rain, snow, dust and the like from penetrating.

In the drawing, as an example of construction a sound direction determining apparatus is shown which is designed for finding targets, moving on the ground. Fig. 1 is a plan view of the sound direction determining apparatus, Fig. 2 is a transverse section of one of the sound leading reflectors.

The sound direction determining apparatus shown has two receiving reflectors *a* and *b* and two sound leading reflectors *c* and *d*. The first named reflectors are shaped as obliquely cut paraboloids while the last named reflectors are in the shape of ellipsoids. One of the receiving reflectors and one of the sound leading reflectors are so connected with each other that the focus of the paraboloid coincides with the outer focus of the ellipsoid. At each of the inner foci of the ellipsoids is located either a microphone or the ear of the sound observer. The two ellipsoids *c* and *d* with the paraboloids *a* and *b* are rotatably mounted in a yoke *I* fixed to an upright *e*, the one *c* being rotat-

able around a pivot *g*, and the other, *d*, being rotatable around a pivot *h*.

A screw *i* rotatably mounted in the upright *e* serves for adjusting the reflectors around the pivots *g* and *h*. Each of the ellipsoids is provided with two longitudinal slots *j*, located in a plane perpendicular to the plane determined by the axes *A*, *A*, *B*, *B*, *C*, *C*, of the reflectors in the example shown in a vertical plane.

The slots *j* may be covered by strips of rubber or the like cemented thereover for preventing rain, snow, dust and so on from penetrating into the reflectors.

What I claim is:

1. A sound direction determining apparatus comprising at least one sound receiving reflector formed of a paraboloid of revolution and at least one sound leading reflector in the form of an elongated ellipsoid of revolution, the said paraboloid and ellipsoid of revolution being confocal, and the sound leading reflector being provided with at least one slot extending in a meridian plane.

2. A sound direction determining apparatus comprising at least one sound receiving reflector formed of a paraboloid of revolution and at least one sound leading reflector in the form of an elongated ellipsoid of revolution, the said paraboloid and ellipsoid of revolution being confocal, and the sound leading reflector being provided with at least one slot extending in a meridian plane perpendicular to the acoustic axis of the preceding reflector.

3. A sound direction determining apparatus comprising at least one sound receiving reflector formed of a paraboloid of revolution and at least one sound leading reflector in the form of an elongated ellipsoid of revolution, the said paraboloid and ellipsoid of revolution being confocal, and the sound leading reflector being provided with at least one slot extending in a meridian plane, the said slot being covered by a sheet of soft material.

In testimony whereof I have affixed my signature.

CHRISTIAN VON HOFE.
